UNITED STATES PATENT OFFICE.

HENRY H. CUTLER, OF MILWAUKEE, WISCONSIN, ASSIGNOR TO THE ARNOLD MAGNETIC CLUTCH COMPANY, OF MILWAUKEE, WISCONSIN, A CORPORATION OF WISCONSIN.

MAGNETIC CLUTCH.

No. 821,020.

Specification of Letters Patent.

Patented May 22, 1906.

Application filed January 18, 1902. Serial No. 90,296.

To all whom it may concern:

Be it known that I, HENRY H. CUTLER, a citizen of the United States, residing at Milwaukee, in the county of Milwaukee and State of Wisconsin, have invented a certain new and useful Improvement in Magnetic Clutches, of which the following is a full, clear, concise, and exact description, reference being had to the accompanying drawings, forming a part of this specification.

My invention relates generally to magnetic clutches, and more particularly to double clutches or clutches designed to drive a movable element at different speeds or in different directions or at different speeds and directions. Such devices are of use in various classes of machinery, among which may be mentioned metal-planers, in which it is desired to drive the bed of the machine in one direction at slow speed and in the reverse direction at a greater speed. In prior devices employing magnetic clutches for this and kindred purposes trouble is experienced in quickly causing the clutch to release or let go the magnetic member, owing to the residual magnetism, and in case of a reversing-clutch, as above mentioned, where one clutching member is intended to release and the other to immediately clutch and rotate the driven part in the opposite direction, the shaft tends to lock and the parts are thus subjected to undue strain.

My invention has for one of its objects the provision of means whereby a sharp and heavy blow is delivered to the sticking armature when it is desired to free the same from the magnet-poles and whereby in the double face or reversing type the said blow is delivered before the reversing clutch is applied.

To these ends and such others as may hereinafter appear the invention comprises in the preferred construction a rotatable or driven member adapted to communicate motion to the desired part, as a planer-bed, the opposite faces of said member having channels formed therein in which are located the magnet-coils. Suitable armature-disks comprising the driving parts are adapted to operate with said magnet-faces and are driven at desired speeds and in opposite directions, whereby when one disk is attracted to the face of the said member the latter is rotated in one direction and when the other

is attracted thereto it is driven in the reverse direction. In order to prevent one disk from coming into contact with the said member before the opposite disk engages therewith, even though the one should cling thereto, a plurality of pins are passed through the said member and are slightly longer than the thickness of the same. A slight play or lost motion is also permitted between the armatures and pins. When, therefore, the current is cut off from one coil and thrown onto the other, the armature of the latter is suddenly attracted and owing to the said play or lost motion acquires considerable momentum before it strikes the said pins, whereby a sharp and heavy blow is delivered to the opposite armature, thus causing it to be freed from the said member. The length of the pins is such that but one disk can be in contact with the said member at a time, whereby all danger from the sticking armature is prevented. The relation of the attracting and attracted members may be reversed and the magnets located in the driving parts instead of in the driven part, but the principle would remain the same.

In the accompanying drawings, Figure 1 is a plan view of the invention as applied to a reversing-clutch. Fig. 2 is a sectional view on the line 2 2, Fig. 1, looking in the direction of the arrows. Fig. 3 is a sectional view on the line 3 3, Fig. 2, the circuit arrangement being also shown. Fig. 4 is a view of a modified arrangement of clutch and gearing as attached to planers; and Fig. 5 is an end view of the gearing.

Like reference characters designate like parts throughout.

In Fig. 1 is shown the motor 2, a large pinion 3 upon one end of its shaft meshing with a gear 4, mounted upon and adapted to rotate the shaft 5, supported in bearings 6, which bearings in case the device is used to operate a planer may be mounted directly upon the frame of the planer. The motor is provided with suitable supporting lugs or feet 7 and may be of any desired type. Upon the other end of the motor-shaft a smaller pinion 8 is carried, which meshes with an intermediate gear 9, supported in suitable bearings 10 and in turn meshing with a gear 11 of special type riding loosely upon the said shaft 5. This gear, as shown in Figs. 2 and

3, is provided with an extended hub 12, having formed integrally therewith the spider-arms 13, through the ends of which bolts 14 are secured, as clearly shown in Fig. 3. These 5 bolts have suitably-formed heads 15, preferably cylindrical, which project through or into apertures of corresponding shape formed in the armature-clutching disk 16, the said disk therefore being carried upon the heads 10 of said bolts and having a slight reciprocating motion thereon.

The driven member 17 has annular channels 18 formed in its opposite faces, in which the magnet-coils 19 are carried. These coils 25 are connected by suitable wires 20 and 21 with the collector-rings 22, 23, and 24, mounted upon the said member and insulated therefrom by the insulating bars or strips 25. Suitable brushes 26, 27, and 28, carried by 30 the suitable stationary support 29, are adapted to bear upon the rings 22, 23, and 24 to make electrical contact therewith. The said brushes are connected with the conductors 30, 31, and 32 of the electric circuit, a switch, 35 such as 33, being provided to shift the circuit from the conductor 30 to the conductor 32. This switch may be conveniently arranged to be automatically shifted by the bed of the planer in its movement. The driving member 40 carries the gear-wheel 35, which is adapted to mesh with the rack-gear carried upon the bed of the planer, although it will be understood that it may intermesh with other gearing or that it may be made in the form of 45 a pulley adapted to communicate motion with the driven parts by means of belts or other connecting devices. A suitable bearing-sleeve 36 is provided for said driven member and provision is made at 37 and 38 for thoroughly oiling the said bearing.

At the side of the driven member on which the gear 35 is located an armature-disk 39, similar to the opposite disk 16, is carried by and adapted to reciprocate slightly upon the 50 heads of bolts 40, secured in the spider-arms 41 of the sleeve 42, the said sleeve being secured to rotate with the shaft 5 by means of the key 43. In order that but one armature-disk may be brought into contact with the driven member at a time, pins 45 extend 55 through the said member and are slightly longer than the thickness of said member, whereby when one of the disks is in contact with the corresponding face of the member the opposite ends of the pins project beyond the adjacent face. A slight play or lost motion is also permitted between the armature-disks 16 and 39 and the pins 45, whereby when an armature is attracted it acquires sufficient 60 momentum before striking the pins to deliver a heavy blow upon the pins and through them upon the opposite armature to free the latter from the face of the driven member.

As shown in Fig. 3, switch 33 closes the 65 circuit through conductors 30 and 31 to the

brushes 26 and 27 and the collector-rings 22 and 23. From here the circuit extends, by means of the connecting-wires, to the coil 19 on that side of the member 17 which is energized and attracts the armature-disk 16 to 70 that face of the driven member and causes them to rotate together, thus driving the gear 35 in one direction at a slow speed. When the switch is changed to its other position to connect with the conductor 32, the 75 current is cut off from the said first coil 19 and passes through the coil in the opposite face, which energizes this side of the driven member and attracts the disk 39. Although the current has been cut off from the coil of 80 the opposite magnet, the armature-disk 16 will cling thereto, owing to the residual magnetism; but the attraction of the armature 39 causes it to strike the pins 45 with sufficient force to separate the disk 16 from the 85 adjacent face of the driven member. The said member is now in physical contact with the armature-disk 39, which is rotating in the opposite direction at a greater speed, and therefore rotates with it in the direction reverse of that before described.

In the modified arrangement of Fig. 4, 50 designates the motor, the shaft of which is provided with an extension 51, carrying the part 17 of the clutch, which is keyed thereto 95 to cause it to rotate with the same. The attracted disks 52, which are shown opposite the faces of the member 17, correspond to the similar disks 16 and 39 of the previous figures. They are likewise carried upon suitable pins 53, which are threaded through the arms of the spiders 13 and 42, carried by the sleeves 12 and 41, respectively. In this form, however, the sleeves ride loosely upon the shaft and are secured to pinions 54 and 55, respectively, which intermesh with gears 56 and 57, carried upon a shaft 58. At the end of the latter shaft a bevel-gear 59 is secured and meshes with a corresponding gear 60, carried by a vertical shaft which is adapted 100 to be connected with the mechanism of the planer in any suitable way. Suitable standards 61 and 62 are secured to the planer-bed 63, carrying the shaft 58 and extension 51 of the motor-shaft. In this form of the invention the size of the clutch may be materially reduced and its cost lessened. The clutch proper or the member 17 is secured directly to the motor-shaft, and as it carries the coils it is of considerable weight and serves the purpose of a fly-wheel upon said shaft. The gears remain stationary even when the motor is running if neither side of the clutch is energized. It is not necessary to form the gear-teeth upon the member 17, as in the 115 case of the form of invention shown in Figs. 1, 2, and 3. The same arrangement as to the pins 45 exists in this form as in that previously described.

Having described my invention, what I 130

claim as new, and desire to secure by Letters Patent, is—

1. The combination with clutch members, of a second member, and means to attract either of said clutch members and the second member together, and further means actuated when one of said members is first attracted to release by impact the other of said members, substantially as described.
2. The combination with two clutches, of means actuated when one clutch is energized to release by impact the second clutch, substantially as described.
3. The combination with two clutches adapted to be alternately energized, of means actuated when one of said clutches is energized to release by impact the second clutch, substantially as described.
4. The combination with two clutches adapted to drive machinery at different speeds and to be alternately energized, of means actuated when one of said clutches is energized to release the second clutch by impact, substantially as described.
5. The combination with two clutches arranged to drive machinery in opposite directions and adapted to be energized, of means for causing one of said clutches when energized to release by impact the opposite clutch, substantially as described.
6. The combination with two clutches arranged to operate machinery in different directions and at different speeds, said clutches being adapted to be alternately energized, of means to cause one of said clutches when actuated to release by impact the other clutch, substantially as described.
7. In a magnetic clutch device, the combination with a common member, of two co-operating members, one located opposite each face of the common member, means to cause mutual attraction between said common member and either of said co-operating members, pins carried by the common member and adapted to be engaged by either of said other members when attracted to the common member, said pins being slightly longer than the thickness of the said carrying member and slightly shorter than the distance between said opposing members when one is attracted and the other unattracted, substantially as described.
8. In a magnetic clutch, the combination with a magnet member of two armature members located opposite the faces of said magnet member, means to energize the opposite faces of said magnet member, whereby the adjacent armature member is attracted thereto, pins projecting through the magnet member and adapted to be engaged by said armature members, said pins being slightly shorter than the distance between the two armatures, whereby when one armature is attracted it acquires momentum before striking the pins and thus delivers a blow upon
- the opposite armature substantially as described.
9. In a magnetic clutch, the combination with a clutch member having channels formed in its opposite faces, magnet-coils located in said channels, armature-disks located opposite the said channels and adapted to be attracted by the magnets, pins carried by the clutch member and adapted when one of said armatures is attracted to receive the impact of said armature and deliver it to the opposite armature whereby the latter is released from the clutch member, substantially as described.
10. The combination with a common rotatable member, means for energizing each face thereof, a second rotatable member mounted opposite each said face of said common member, and means when one of said second members is initially attracted to the adjacent face of said common member to release the other second member by the impact of a blow delivered thereto by the said attracted member, substantially as described.
11. The combination with a magnet member, of two opposed members free to rotate independently of each other and adapted to be alternately attracted by said magnet member, and means to release one such member from the magnet member by the other opposed member when the latter is attracted, substantially as described.
12. The combination with a shaft, of a clutching mechanism mounted upon said shaft and comprising a common member, and a second member opposite each face of said common member, means to attract either of said second members and said common member together, and further means actuated when one of said second members and the common member are initially attracted together to release the other of said second members from said common member by the impact of a blow delivered thereto, substantially as described.
13. In a magnetic clutch, the combination with a rotatable main body and an energizing-coil located on each side of said main body, of independently-rotatable armatures, one on each side of said main body, and a sliding rod extending through said main body of a length somewhat greater than the width of said main body, whereby as one armature moves up to said main body the other is forced away therefrom.
14. In a variable-speed device, a revolvable shaft, a magnet having a plurality of coils fastened thereon, independent transmitting-wheels loosely mounted on said shaft, an armature rigidly connected with each of said wheels each armature facing a pole or poles of said magnet, means for controlling the energization of the actuating-coils of the magnet independently of each other, and means for preventing said armatures from simulta-

neously contacting with their respective magnet-faces when the coils of said magnet are energized.

15. In a variable-speed device, a revoluble shaft, a magnet having a plurality of coils fastened thereon, transmitting-wheels of different diameters loosely mounted on said shaft, an armature rigidly connected with each of said wheels each armature facing a pole or poles of said magnet, means for controlling the energization of the magnet-coils independently of each other, and means for preventing said armatures from simultaneously contacting with their respective magnet-faces when the coils of said magnet are energized, said means comprising a rod or rods extending through said magnet and having a length slightly greater than the distance between the opposing faces of said magnet.

20. 16. In a variable-speed mechanism, a revoluble shaft, a magnet fastened thereon, independent transmitting-wheels loosely mounted on said shaft each of said wheels being fastened to a disk which faces a pole or poles of the magnet and forms an armature therefor, and a rod or rods passing through said magnet whereby said armatures are prevented from simultaneously contacting with the opposing faces of said magnet.

25. 17. In combination, a revoluble shaft, a double-faced electromagnet mounted on said shaft, two, independent armatures loosely mounted on said shaft and adapted to coact with the opposing faces of said magnet, and a rod or rods carried by said magnet for the purpose of forcing one armature away from its magnet-face when the other armature is in contact with its magnet-face.

30. 18. In a magnetic clutch, the combination with the main body and energizing-coils located on either side of said main body, of relatively rotatable armatures on opposite sides of said main body, a sliding rod extending

through said main body of a length somewhat greater than the width of said main body, whereby as one armature moves up to said main body the other is forced away therefrom.

35. 19. The combination with two independently-rotatable bodies or members, of a third or central body arranged between said independently-rotatable bodies, electromagnetic windings for bringing either of said independently-rotatable bodies into operative relation with said third body, and means whereby when one of said independently-rotatable bodies is in operative relation with said third body the other independently-rotatable body is forced away from said third body.

40. 20. The combination with two relatively movable bodies, of a third or central body, electromagnetic windings for bringing either of said relatively movable bodies into engagement with said third body, and means whereby when one of said relatively-movable bodies is brought into engagement with said third body the other relatively movable body is forced away from said third body.

45. 21. The combination with two relatively movable bodies, of a third or central movable body, electromagnetic windings for bringing either of said relatively movable bodies into engagement with said third body, and a rod supported by said third body for forcing one of said relatively movable bodies away from said third body when the other relatively movable body is in engagement with said third body.

50. In witness whereof I have hereunto subscribed my name in the presence of two witnesses.

HENRY H. CUTLER.
